UNITED STATES PATENT OFFICE.

DAYTON BUMGARDNER, OF CHICAGO, ILLINOIS.

DENTAL VIBRATORY APPARATUS.

Application filed January 30, 1922. Serial No. 532,747.

To all whom it may concern:

Be it known that I, DAYTON BUMGARDNER, a citizen of the United States, and a resident of the city of Chicago, county of Cook, and 5 State of Illinois, have invented certain new and useful Improvements in Dental Vibratory Apparatus, of which the following is a specification.

My invention relates to dental vibratory 10 apparatuses, and has for its principal object the provision of a construction of this character which is especially adapted for condensing composition used to form models, such as are made from an impres- 15 sion of teeth.

The object of the invention is such that the composition, of which the model is formed, will be caused to condense by subjecting the impression, from which the 20 model is formed to a vibratory treatment while the composition is being fed into the impression. By this arrangement the composition, which is in the form of a plastic substance, when fed into the impression, is 25 caused to condense and force the moisture contained in the composition to the surface. This vibratory treatment causes the air bubbles to disappear which would otherwise disfigure the model when hardened or interfere 30 with the durability of the same and the moisture is caused to rise to the surface of the composition which permits the composition to readily harden inasmuch as by the vibratory treatment the core or innermost 35 portion of the model is to a great extent free from moisture. After the composition is completely hardened, the impression, which is of a wax composition, or any other impression material, is removed and the model is 40 then subject to further treatment which is well known in the dental art.

Other objects will appear hereinafter.

The invention consists in the combinations and arrangements of parts hereinafter described and claimed.

The invention will be best understood by reference to the accompanying drawings forming a part of this specification, and in which,

Fig. 1 is a side elevational view of a device embodying the invention;

Fig. 2 is a top plan view, of the same, showing the vibrating means attached to a motor;

Fig. 3 is a plan view of the vibrating means embodied in the invention;

Fig. 4 is a sectional detail view of an impression; and

Fig. 5 is a perspective view of a model formed from the impression illustrated in Fig. 4.

In carrying the invention into effect, I provide a vibratory member A which is in the form of a swingingly mounted arm 10 bent in the form illustrated in Fig. 1. The arm 10 is preferably formed of spring steel which in this instance is in the form of a narrow plate, as shown, the foot 11 of the arm 10 is provided with an elongated slot 12 arranged and adapted to slidably engage a bolt 13 which is preferably screwed in a socket member 14 sunk into the top 15 of a work bench or the like. At one end of the slot 12 is an opening 16 which is of a diameter a trifle larger than the head of the bolt 12 to permit the arm 10 to be removed when not in use. The horizontal portion 17 of the arm 10 carries a platform 18, which, as shown, is rectangular in shape and fixedly secured to the said portion by suitable rivets 19. The platform 18 and the means for securing the same to the horizontal portion can be of any approved shape or means which will answer the purpose.

The means for causing the arm to vibrate 85 is in this instance in the form of a polygonal cam member 20, arranged under the horizontal portion 17 in spaced relation with respect thereto, carried by a screw threaded tapered spindle 21, said polygonal member 90 being formed of fibre or any other suitable material. The end 21' of the spindle 21 is provided with a socket 22 for the reception of the end of the shaft 23 of a power driven motor 24. The spindle 21 can be removably secured to the shaft 23 by any suitable means, but in this instance the shaft 23 of the motor 24 is arranged to frictionally engage the socket portion of the spindle 21.

Carried by the platform 18 and extending 100 downwardly therefrom is a finger 25 which is arranged to contact with the hub 26 of the polygonal member 20 when in operative position. The purpose of the finger 25 is to control the swinging movement of the arm 10 when swung in operative position.

In use, the impression B, which is of any shape or size, illustrated in Fig. 4, is held

in one hand by the operator and permitted to freely rest on the platform 18, the hand serving to retain the impression on the platform 18. By manually applying a downwardly pressure to the arm 10 the horizontal portion 17 is brought into contact with the hexagonal member 20 which is rotated by the power driven motor 24. This contacting of the horizontal portion 17 of the arm 10 is caused to vibrate upon rotation of the polygonal member 20. The amount of vibration transmitted to the vibratory member A depends upon the pressure applied to the horizontal portion 17, that is to say, that 15 the greater the pressure, the greater the vibration. As the composition is fed into the impression the vibration of the vibratory member A causes the composition to spread out and pass into the deep impressions which 20 are usually found in the impression as well as causes the composition to condense and raise the moisture to the top surface of the said composition. The operator continues to gradually feed the composition 25 into the impression until the impression is completely filled. At this stage the composition has the appearance of putty and if the form should be broken open, the core of the same would be found to be in a semi- 30 state of dryness, that is to say, going through the process of hardening. As herein stated the vibratory treatment causes the composition to condense and raises or forces the moisture to the top surface thereof, the 35 advantage being that the moisture is forced from the core or innermost part of the composition to the top thereof, greatly facilitating the hardening of the composition. After the composition is properly hardened 40 within the impression B the impression is cut away from the hardened composition, leaving the model C, as shown in Figure 5, in its finished state.

While my vibratory apparatus is especially adapted for condensing the composition, of which the model C is formed from an impression B it also can be adapted to various other usages.

While I have illustrated and described the 50 preferred form of construction for carrying my invention into effect, this is capable of variation and modification without departing from the spirit of the invention. I, therefore, do not wish to be limited to the 55 precise details of the construction set forth, but desire to avail myself of such variations and modifications as come within the scope of the appended claims.

Having described my invention, what I 60 claim as new and desire to secure by Letters Patent is:

1. An apparatus for compacting the composition of a dental model during the feeding of the composition in a dental impression comprising in combination with a

motor, of a tapered spindle carried by the shaft of said motor; a polygonal cam member carried by said spindle; and a vibratory member adapted to be swung and forced into contact with said member, substantially as described. 70

2. An apparatus for compacting the composition of a dental model during the feeding of the composition in a dental impression comprising in combination with an electric motor, of a polygonal cam member carried by the shaft of said motor; a vibratory arm adapted to be swung and forced into contact with said member; and a platform carried by said arm above said member, substantially as described. 75

3. In an apparatus for compacting the composition of a dental model during the hardening thereof comprising a swingingly mounted vibratory arm; means for vibrating 80 said arm; and a platform carried by said arm over said vibrating means.

4. In an apparatus for compacting the composition of a dental model during the hardening thereof comprising a polygonal 90 cam member; a vibratory member adapted to be swung and forced into contact with said member; and a guide member carried by said vibratory member adapted to engage the hub of said polygonal member when 95 in operative position.

5. In an apparatus for compacting the composition of a dental model during the hardening thereof comprising a rotatable polygonal member; a vibratory arm mounted to swing and be forced into contact with said member; means for controlling the swinging movement of said vibratory member; and a platform carried by said vibratory member over said hexagonal cam member. 100

6. An apparatus for compacting the composition of a dental model during the feeding of the composition in a dental impression comprising in combination with a socket member; of a screw threaded bolt engaging said socket member; a vibratory member removably held by said bolt; and means for vibrating said member, substantially as described. 110

7. An apparatus for compacting the composition of a dental model during the feeding of the composition in a dental impression comprising in combination with a socket member of a screw threaded bolt engaging said socket member; a vibratory member, there being an elongated slot formed in one end of said vibratory member for the reception of said bolt; and a polygonal member adapted upon contacting 120 with said vibratory member to cause said vibratory member to vibrate, substantially as described.

8. An apparatus for compacting the composition of a dental model during the feed- 130

- ing of the composition in a dental impression comprising in combination with a socket member; of a screw threaded bolt engaging said socket member; a vibratory arm 5 adapted to slidably engage said bolt; a polygonal member arranged in spaced relation with said vibratory arm adapted upon contacting with said arm to vibrate said arm; a depending guide finger carried by said arm 10 adapted to engage the hub of said polygonal cam member; and a platform carried by said vibratory member above said polygonal cam member, substantially as described.
- 15 9. An apparatus for compacting the composition of a dental model during the feeding of the composition in a dental impression comprising in combination with an electric motor, of a tapered spindle frictionally carried by the shaft of said motor; a fibre polygonal cam member carried by said spindle; a vibratory arm adapted to be swung and forced into contact with said polygonal cam member; and means for removably mounting said vibratory arm on a work bench or the like, substantially as described.
10. An apparatus for compacting the composition of a dental model during the feeding of the composition in a dental impression comprising in combination with an electric motor, of a tapered screw threaded spindle frictionally carried by the shaft of
- 35 said motor; a fibre polygonal cam member removably carried by said spindle; a vibratory means arranged above said polygonal cam adapted to be forced into contact with said member.
11. A dental apparatus comprising in combination with a motor of a spindle frictionally carried by the shaft of said motor; a polygonal member carried by said spindle; a platform mounted to be swung over said member and pressed into engagement therewith; and means associated with said platform adapted to control the swinging movement of said platform when swung into operative position.
12. The combination of a motor, a spindle carried by the shaft of said motor, a cam 50 mounted upon said spindle, an upwardly inclined resilient bar pivotally supported at its lower end, and extending over and into operative relation with said cam at its upper end, said bar being movable upon said pivot 55 into and out of operative relation with said cam, and a receptacle mounted upon the upper portion of said bar.
- In testimony whereof I have signed my name to this specification in the presence 60 of two subscribing witnesses.

DAYTON BUMGARDNER.
